UNITED STATES PATENT OFFICE.

WALTER B. PAYNE, OF ROCHESTER, NEW YORK, ASSIGNOR TO TODD PROTECTOGRAPH CO., INC., OF ROCHESTER, NEW YORK.

PRINTING APPARATUS.

Application filed May 23, 1922. Serial No. 563,153.

To all whom it may concern:

Be it known that WALTER B. PAYNE, a citizen of the United States of America, residing at Rochester, in the county of Monroe 5 and State of New York, has invented certain new and useful Improvements in Printing Apparatus, of which the following is a specification.

This invention relates to printing apparatus of the general variety adapted for printing legends such as monetary values on checks, and instruments of a like nature, as represented, for example, by the machine disclosed in Letters Patent No. 1,138,330 to 15 L. M. Todd and C. G. Tiefel dated May 4, 1915, having as one of its chief objects the provision in such an apparatus of an efficient power-operated driving mechanism for increasing its convenience and speed of operation.

Another object is to provide a simple and practical driving mechanism conveniently controlled by means associated directly with one of the parts for manipulating the printing apparatus, whereby the rapidity of operation is increased and but a single hand of the operator is required to accomplish the printing, leaving the other hand free to manipulate the work.

30 A further object is to provide driving mechanism of the above character comprising an electric motor compactly mounted on the frame of the printing machine and connected with the latter by simple, efficient and reliable mechanism completely controlled by movement of the same member which is employed to select the type forms, so that as each form is selected it may be quickly printed by the same operating member.

40 To these and other ends the invention consists in certain improvements and combinations of parts all as will be hereinafter more fully described, the novel features being pointed out in the claims at the end of 45 the specification.

In the drawings:

Fig. 1 is a central, longitudinal section, partly broken away, of a machine of the variety shown in said Letters Patent having 50 the invention applied thereto.

Fig. 2 shows the resistance device or reducer.

Fig. 3 is a section on the line 3^a—3^a, Fig. 1.

Fig. 4 is a section on the line 4^a—4^a, Fig. 1.

55 Fig. 5 is a section on the line 5^a—5^a, Fig. 1.

Fig. 6 is substantially the same as Fig. 5 but shows the mechanism at a different point in the operation of the machine.

Fig. 7 is an end view of the resistance device or reducer.

Fig. 8 is an end view of the machine with the cover removed to show the mechanism.

Fig. 9 shows the clutch mechanism for effecting variable operation of the main shaft.

Fig. 10 is substantially the same as Fig. 9, 65 but shows the mechanism at a different point in the operation of the machine.

Fig. 11 is substantially the same as Fig. 9 but shows the position of the mechanism when the indicator is at the "re-ink" position.

Fig. 12 is a top view of the illustrative machine with the invention applied.

Fig. 13 is a section on the line 13^a—13^a, 70 Fig. 8.

Fig. 14 is a detail of the means for connecting up the motor shaft.

Fig. 15 is a top view of the actuating handle centering and locking mechanism.

The invention is embodied in the present instance in a machine of the well known variety disclosed in said Letters Patent to Todd and Tiefel, which may be generally described as comprising a type carrier splined on a rotary main shaft along which it may be moved by means of a selecting mechanism to bring a plurality of separate type forms on the carrier individually and selectively to position for rolling co-operation with a rotary platen suitably supported below the bed of the machine. The work is placed on the latter between the members of the printing couple, which are rotated after each selective movement such as described to simultaneously print and feed the work, the selective movements for bringing the type forms in succession to printing position alternating with printing movements effecting impression of the selected forms. As this type of machine is fully described in 85 said Letters Patent and well known in the art, description of all of the details thereof is unnecessary, but for the purpose of convenience in the present instance various details entering more particularly into combination with the present improvement are 90 hereafter described.

Referring more particularly to the drawings, there is shown a main frame, including a base 20 (Fig. 1), in which a portion of 100

the mechanism is mounted, and a top casing 21 in which the remainder of the mechanism is mounted, and which is hinged at 22, Fig. 12, to the base. Latches (not shown) serve to hold the top against movement relative to the base when the machine is in operation. The top of the base 20 is suitably constructed to act as a bed or table for the work, and is provided with openings through one of which a platen 38 extends and operates. The hinged top is cut away, as shown at 23, to provide a clearance so that the work may be fed through the machine.

A main shaft 24 is journaled in one of the end walls of the top casing 21, and extends through the other end of the casing, into an enclosure which contains the major portion of the mechanism embodying this invention, the shaft 24 being journaled near this end in the other end 26 of the top casing which portion 26 forms the back of the enclosure, and which is provided with a bottom 25, and a top 27, a cover 28 being secured to the top and bottom.

Secured to the forward end of the shaft 24 is a gear 29 meshing with a gear 30 attached to the inner end of a shaft 31 journaled in a boss 32 (Fig. 12) on the side of the casing. It has heretofore been customary in machines of the Todd and Tiegel type to which the present invention is shown applied to provide a handle on the outer end of the shaft 31, by means of which the shaft 31 may be rotated, the movement being transmitted by means of gears 30 and 29 to the shaft 24. With the present invention applied, however, the shaft 24 is not rotated by means of the shaft 31, and a cup 33 is supplied to cover the end of the boss 32.

The type to be printed from extend circumferentially of the carrier and are spaced from one another axially thereof, as represented generally by the numeral 34 (Fig. 1). The type carrier 35 is splined on the main shaft 24 so that it may be moved lengthwise of the shaft, while rotation of the shaft will cause the type carrier to be rotated with it.

Loose on the shaft 24 and embracing the type carrier 35 are the arms of a yoke 36, provided with a handle 37 whereby the yoke 36 and the type carrier therein may be shifted to different positions along the shaft 24. In this way any line of type 34 may be brought into alignment with the platen 38, a pointer 39 rigid with the handle 37 co-operating with a dial 40 (see Fig. 12) to aid the operator in setting the desired line of type in position to co-operate with the platen.

The platen 38, which is mounted in a yoke 41, is normally held in a lowered position, but when the machine is operated to print, the platen is raised by means of a cam on the shaft 24 and a bar attached to the yoke 41, and co-operates with the selected type

line to print and also to feed the work through the machine during the printing operation.

The mechanism for inking the type comprises rollers 42 (Fig. 5) supported in axial alignment with the type carrier, and engaged by the type lines 34 as the type carrier is rotated. The rollers are of felt or other suitable material, and are preferably each divided into two portions, one longer than the other, and the shorter portions supplied with ink of a different color from that supplied to the longer portions, usually black on the shorter and red on the longer portions, so that part of the type characters are inked with black ink and part with red ink. In the illustrative machine the portions supplied with black ink ink the type corresponding to the positions 43, Fig. 12, on the dial, while the portions supplied with red ink ink the type printing the words 44. Between these two groups of type characters a blank space occurs on the type carrier and a corresponding space occurs on the ink rolls opposite this space on the type carrier, this space on the ink rolls serving to separate the portions supplied with red ink from those supplied with black. The position on the dial that corresponds to this blank space on the type carrier is marked "Re-ink." When the pointer 39 is brought to this position and the type carrier is rotated, no type line will be in register with the platen, so that the only result will be the inking of the type characters.

Secured to the yoke 36 near one end is preferably a formed member 45 (Figs. 1 and 4) to which is fastened a block 46. Secured to the casing 21 is a bracket 47 (Fig. 1) in which is journaled one end of a shaft 48. This shaft extends into the enclosure secured to the casing 21, and is journaled near its other end in the casing portion 26. Rigidly secured to the shaft 48, and parallel with it, is a bar 49 equal in length to the space occupied by all the positions on the dial 40. This bar is provided with a formed edge 50 (Fig. 4) with which the block 46 co-operates.

The yoke 36, being loosely mounted, is capable of being rocked on the main shaft 24, and since the handle 37 is secured to the yoke and projects out from it, any downward pressure on the handle 37 will rock the yoke 36, and also the member 45 which is secured to it. This motion of the member 45 will be transmitted to the block 46, and since the edge 50 is at all times held in contact with the block 46 by the action of a spring 51 (Fig. 1) on the shaft 48, the rocking motion imparted to the block 46 will cause the bar 49 to be rocked, thus rocking the shaft 48 in an anti-clockwise direction (Fig. 4). In order to limit the movement of the handle 37 and also to insure the correct

positioning of the selected type line prior to the printing operation, a rack 52 (Figs. 4 and 15) is secured to the underside of the top of the casing 21, provided with teeth 53 to form notches engaged by a wedge-shaped end 54 provided on a formed member 544 secured to the yoke 36 adjacent the member 45. The notches in the rack 52 correspond to the positions on the dial 40, there being a notch for each position.

Secured to one end of shaft 48 is an arm 55 (Fig. 9), to one end of which is pivoted a pawl 56 provided with a shoulder 57 and an arm 58. Pivotally mounted on the casting 16 26 is a member provided with arms 59 and 60. The arm 59 is provided with a formed end 61, co-operating with the shoulder 57, and the arm 60 is provided with a formed end 62 reinforced by a stiffening lug 63 projecting also from the arm 60, (Figs. 1 and 9). Springs 64 and 65 act to normally hold the formed end 61 against the shoulder 57.

Secured to the main shaft 24 near one end is a disc 66 (Figs. 1 and 9) on which is mounted a stud 67 (see Fig. 1) carrying an arm 68 pivotally mounted and provided with an ear 69 and a shoulder 70. The disc 66 is provided with an opening 71 through which the ear 69 operates. The spring 64 also acts to hold the arm 60 down so that its end 62 will normally engage the shoulder 70 and hold the arm 68 in a raised position, against the action of a spring 72 secured to one end of the arm 68 and to an ear 73 on the disc 66, the spring 72 being normally extended.

Mounted loosely on the main shaft 24 at one end is a collar 74 (Fig. 1) to which is secured a bevel gear 75 provided with an extension in which are cut openings 76 to form sections or teeth 77 (see also Fig. 9.) Mounted on top of the casing 21 is an electric motor 78 of a suitable size and type, connected by means later to be described with 45 a driving shaft 79 (Figs. 1 and 8) mounted in the casting 26 and provided at its lower end with a bevel gear 80 meshing with the gear 75. When the machine is in use the motor 78 is in constant rotation, so that the gear 75 and its extension containing teeth 77 are also constantly rotating, being driven by the gear 80.

When the handle 37 is depressed and the shaft 48 consequently rocked as above described, the arm 55 will be rocked in an anti-clockwise direction (Fig. 9), as a result of which the shoulder 57 of the pawl 56 will bear against the end 61 of the arm 59. As a result of this action the arm 60 and the end 62 will also be rocked anti-clockwise. When the end 62 has cleared the shoulder 70 the action of the spring 72 will draw the arm 68 downward until the ear 69 is engaged by one of the teeth 77. Since the teeth 77 are constantly rotating anti-clockwise (Fig.

9), the arm 68 and consequently the disc 66 will now be rotated along with the teeth 77. Shortly after the disc 66 has been thus set in motion the stud 67 will engage the end of the arm 58 and rock the arm clockwise against the action of the spring 65, causing the shoulder 57 to disengage the end 61 of the arm 59, thus allowing the arm 60 to be returned by the spring 64 to its starting position, as shown in Fig. 10. Further rotation of the disc 66 will bring the shoulder 70 back to its starting position, at which point it will be engaged by the end 62 of the arm 60, causing the arm 68 to be swung on its pivot and the ear 69 to be moved out of engagement with the teeth 77.

Before the handle 37 can now be moved to a different position on the dial it will be necessary to release the pressure on the handle and allow it to be raised by the action of the spring 51, thus disengaging the wedge 54 from the rack 52. When the handle 37 is thus raised, the shaft 48 will be rocked clockwise, (Fig 9), causing the arm 55 to be rocked with it, as a result of which action the pawl 56 and arm 58 will be returned to their starting position by the action of the spring 65. This completes the action of the clutch mechanism, all the parts being now in their normal or starting position. In order to prevent the disc 66 from being rotated in the wrong direction a shoulder 81 (Fig. 9) is provided on the disc 66, co-operating with a pawl 82 pivotally mounted on a stud secured to the casting 26. The spring 64, one end of which is fastened to an ear on the pawl 82, acts to hold the pawl against the periphery of the disc 66 at all times.

As before stated, there is a blank space on the type carrier between the group of words inked to print red and the group inked to print black, denoted on the dial as the "re-ink" position. When it is desired to ink the type lines without printing any character the indicator 39 is brought to this "re-ink" position, it being then possible to rotate the type carrier with no type line in printing position. It will be apparent that with the indicator in this position it is desirable to have the type carrier rotate continuously while the handle 37 is depressed, in order that the type may be thoroughly inked, without the necessity of tripping the handle 37 for each revolution of the type carrier. In order to accomplish this there is secured to the member 544 a formed member 83 (Figs. 1 and 4) provided with a projection 84 for co-operation with the projecting end 85 of a bar 86 loosely mounted on the shaft 48. The bar 86 is also provided at its other end with an arm 87 (see Figs. 1 and 5) provided with a formed end 88 operating through an opening in the casting 26 to co-operate with an ear 89 on the arm 60 (see also Fig. 10).

1,505,666

When the indicator 39 is at the "re-ink" position, the projection 84 will be opposite the projecting end 85 of the bar 86. Depression of the handle 37 will now cause the projection 84 to bear against the end 85, thus rocking the bar 86 and the arm 87 anti-clockwise (Fig. 5). As a result of this action the end 88 will engage the ear 89 and raise the arm 60, as shown in Fig. 6, causing the end 62 to disengage the shoulder 70 and leave the disc 66 free to be rotated. It will be seen that as long as the handle 37 is depressed the end 88 will be held in engagement with the ear 89, so that the end 62 will be held out of engagement with the shoulder 70, and the arm 68 thus allowed to remain in operable position. When the handle 37 is now released the action of the spring 51, one end of which bears against the bar 86, will return the bar 86 to its starting or normal position, leaving the arm 60 free to be acted upon by the spring 64 and rocked so that the end 62 will assume its normal position and engage the shoulder 70.

As mentioned above, the motor 78 is mounted on the casing 21, and connected with a driving shaft 79. This connection is preferably made as follows: Secured to the upper end of the shaft 79 is a worm gear 90 (Figs. 8 and 13) meshing with a worm 91 on a shaft 92 journaled in the casting 26. The motor 78 is also provided with a shaft 93 (Fig. 1). In order to obviate the necessity of precisely mounting and accurately maintaining the position of the motor 78 so that the shaft 93 will also be accurately positioned, there is provided rigid on the end of the shaft 93 a member 94 provided with two ears 95 (see also Fig. 14) which engage notches 96 in a disc 97. The shaft 92 is also provided at one end with a member 98 (see Fig. 13) similar to member 94 and also provided with ears 99 but disposed in an opposite direction to ears 95, and engaging notches 100 in the disc 97. Thus when the shaft 93 is rotated the ears 95 will engage the notches 96 and rotate the disc 97, which in turn will rotate the shaft 92 by means of the notches 100 and ears 99.

In order to provide a substantially constant load for the motor and thus secure a fairly even rate of speed at all times, there is provided loose on the shaft 24 and rigid with the collar 74 a disc-shaped member 101 (Figs. 1 and 8) made of tempered sheet metal and formed bowl-shaped so as to have its rim bearing at all times against a disc 102 (Fig. 1) loose on the shaft 24. The disc 102 is composed of fibre or other suitable material, and is at all times held by the member 101 against a metal disc 103 rigid with the shaft 24. A cap 104 which screws on the end of the shaft 24 holds the disc 103 in position, the degree of pressure of the member 101 against the disc 102 being adjustable by means of the cap 104. Thus when the shaft 24 is idle and the collar 77 is rotating, the friction caused by the member 101 bearing against the disc 102 or the friction of the disc 102 against the disc 103, as the case may be, will serve to retard the gear 75 and motor 78, and impose a regulating load on the latter to maintain its speed substantially constant. When the handle 37 is depressed, however, and the shaft 24 rotated, the disc 103 will rotate with the shaft 24, and with the member 101, thus eliminating all friction between the member 101 and the disc 102 or the disc 103.

As above described, the collar 74 is in constant rotation while the machine is in use. In order to insure proper lubrication at this point the shaft 24 is drilled at its end to provide a boring 105 connecting with holes 106 (one on either side of the shaft) opening underneath the collar 74. The boring 105 is filled with a suitable lubricant, which, during the rotation of the shaft 24 flows out of the holes 106. The boring 105 is tapped to receive a screw 115 which acts as a closure for the boring.

The wiring of the machine is as follows. The feed wires enter through a hole 107 (Fig. 8) in the side of the casting 26. From here one of the wires is led to a plug section 108 secured to the bottom 25. This plug is composed of two sections, 108 and 109 (Fig. 1), each having a pair of contacts and plug 109 being located in base 20, so that the machine may be opened, the top 22 hinging on the base 20 as heretofore described. When the machine is open, springs (not shown) in the section 109 serve to hold the ends of the two contacts in that section slightly projecting, and when the machine is closed, serve to hold the ends of the contacts snugly against the ends of the corresponding contacts in the section 108. The wire is then led to a resistance device 110 (Figs. 1, 2 and 7) secured to the underside of the bottom 20. This device is provided to accommodate the motor to variations in voltage and other operating conditions, and comprises a sliding member 111 (Fig. 2) capable of contacting at various points along a member 112 and thus increasing or decreasing the amount of resistance in the circuit. The wire above mentioned is fastened to the member 111. The return wire is fastened to the member 112 at one end, from which it is led back through the plug section 109, thence through 108, and thence to the motor 78, from which it is led to a switch 118 (Figs. 1 and 8) secured to the top 27 of the casting 26, and provided with a handle 114. The other feed (or return) wire is led directly to the switch 118.

The operation of the mechanism has been described in detail in connection with the above explanation of the construction, and

1,505,666

- may be briefly summarized as follows: The selecting member or handle 37 having been moved to register with the position marked "Release" on the dial, the work is located 5 on the printing bed, and the selecting member then moved to register with the word "Exactly," thereby sliding the carrier to bring the corresponding type form to position for co-operation with the platen.
- 10 Handle 37 is then depressed, and through the connecting mechanism described, shaft 48 is thereby rocked to trip the stop device formed by arms 59 and 60. The clutch part formed by arm 68 is thus released for movement into engagement with the continuously rotated clutch part 75. This starts a rotation of disc 66 and the main shaft and type carrier to effect a printing impression of the selected type form. During such rotation, 15 however, arm 58 is engaged and tripped by stud 67, releasing the stop device, which is returned to position for engagement with the clutch part 68 when the latter completes a rotation and returns to starting position.
- 20 The clutch parts are thus automatically disengaged after each complete rotation of the carrier, ready for the selection and printing in a similar manner of the next and succeeding type forms until the desired legend is 25 fully printed on the work. The operation of the machine may thus be accomplished entirely by the hand of the operator which manipulates the selecting handle 37, so that the other hand is left free to attend to the 30 control of the work. This arrangement by which not only the selection but also the control of the operating mechanism is effected by common handle 37 increases not only the convenience but the speed of operation of the machine. When it is desired to 35 produce continuous idle rotation of the carrier in order to ink the type forms, handle 37 is moved to bring the index 39 into registry with the designation "Re-ink" on the dial, and depressed, which, by the means described, rocks bar 86 so that its end 88 raises arm 60, and maintains the same in raised position. The clutch parts are thus left in engagement with each other for continuous rotation of the carrier until handle 40 50 55 is again raised.
- It is apparent from the above description that the driving mechanism is simple, efficient and reliable in character, and convenient and rapid in operation.
- I claim:
1. The combination with a plurality of type forms and platen having relative selective movement to bring the type forms individually to position for co-operation with the platen and said type forms having also a rotary printing movement, and a single manually operable means for effecting said selective movement, of power driven means comprising a rotary part, a rotatable part 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940
2. The combination with a type carrier having a plurality of separate type forms in spaced relation thereon, and a platen, said carrier having a selective movement to bring the type forms individually to position for co-operation with the platen and having also a printing movement, of power driven means having an actuating part, a part connected with the carrier for effecting said printing movement, thereof and a single manually operable means comprising a device for temporarily connecting said parts to effect the printing movement of the carrier.
3. The combination with a type carrier and platen having a relative reciprocating movement to bring a plurality of type forms on the carrier selectively to position for co-operation with the platen and having also a relative rotary movement to print and feed the work, of power driven means having a rotating actuating part, a rotatable part connected with one member of the printing couple and manually operable means for effecting said relative reciprocating movement comprising a device for temporarily connecting said parts to effect said rotary printing movement.
4. The combination with a printing couple comprising a type carrier having a plurality of type forms thereon and a platen, said carrier and platen having a relative selective movement to bring the type forms individually to position for co-operation with the platen and having also a relative printing movement, of continuously driven power operated means, connecting means including a clutch device, for connecting said power means with the printing couple, and a single manually operable means for effecting said relative selective movement of the type carrier and platen and for actuating said clutch device to intermittently effect said printing movement thereof.
5. The combination with a printing couple comprising a plurality of type forms and a platen having a relative selective movement to bring the type forms individually to position for co-operation with the platen and having also a rotary printing movement to impress the selected type form on the work, of power driven means having a connection including a clutch device for connecting the same with the printing couple, and manually operable means for alternately effecting said selective movement of the type forms and platen and actuating said clutch device to effect said printing movement thereof.
6. The combination of a platen, a plu-

- 6
1. The combination with a type carrier and platen having a relative selective movement to bring a plurality of type forms and also a blank portion on the carrier individually into registry with the platen, and inking means for the type forms, said carrier having a movement for bringing the type forms into co-operation with the inking means and for printing a selected type form, of continuously driven power operated means, mechanism for connecting said power means with the carrier to produce either continuous or intermittent single movements thereof, and a manually operable device for effecting said selective movement of the carrier and platen connected also with said mechanism for producing continuous inking movement of the carrier when said blank portion registers with the platen and intermittent single movements thereof when said type forms are in registry with the platen. 70
2. The combination of a printing couple comprising a platen, a type carrier shiftable to bring a plurality of type forms thereon selectively and individually to position for co-operation with the platen, said carrier and platen having also a relative rolling printing movement, power driven means including rotary clutch parts, controlling means for connecting and disconnecting said power means with the printing couple to effect said printing movement, and manually operable means for shifting said carrier to select the type forms having an additional movement in any selected position for actuating said clutch parts to effect a printing movement. 80
3. The combination of a rotary platen, a type carrier shiftable to bring a plurality of type forms thereon selectively and individually to position for co-operation with the platen, said carrier having also a printing movement in rolling coaction with the platen to print and feed the work, power driven means for effecting said printing movement of the carrier, controlling means for said power means, and a device movable to effect said selective shifting movement of the carrier and connected with said controlling means and having an additional movement for operating the latter and the power means to effect a printing movement of the carrier. 90
4. The combination with a type carrier and platen having a relative selective movement to bring a plurality of type forms and also a blank portion on the carrier individually into registry with the platen, and inking means for the type forms, said carrier having a movement for bringing the type forms into co-operation with the inking means and for printing a selected type form, of continuously driven power operated means, mechanism for connecting said power means with the carrier to produce either continuous or intermittent single movements thereof, and a device controlling said mechanism for producing continuous inking movement of the carrier when said blank portion registers with the platen and intermittent single movements thereof when said type forms are in registry with the platen. 100
5. The combination with a type carrier and platen having a relative selective movement to bring a plurality of type forms and also a blank portion on the carrier individually into registry with the platen, and inking means for the type forms, said carrier having a movement for bringing the type forms into co-operation with the inking means and for printing a selected type form, of continuously driven power operated means, mechanism for connecting said power means with the carrier to produce either continuous or intermittent single movements thereof, and a manually operable device for effecting said selective movement of the carrier and platen connected also with said mechanism for producing continuous inking movement of the carrier when said blank portion registers with the platen and intermittent single movements thereof when said type forms are in registry with the platen. 110
6. The combination with a type carrier and a rotary platen, said carrier having an axial sliding movement to bring a plurality of type forms thereon selectively and individually to position for co-operation with the platen and having also a rotary movement with a selected type form in rolling coaction with the platen to print and feed the work, of continuously driven power operated means, mechanism for connecting said power means with the carrier adapted to effect a single rotary printing movement thereof, and a manually operable device for effecting said selective axial movement of the carrier having a connection with said mechanism for actuating the latter after each selection of a type form to print the latter on the work. 120
7. The combination with a printing couple comprising a plurality of type forms and a platen having a relative selective movement to bring the type forms individually to position for co-operation with the platen and having also a relative printing movement, of continuously driven power operated means, mechanism for connecting said power means with the printing couple to effect the printing movement thereof comprising engagable clutch parts means tending to engage said parts, and a trip device arranged to automatically disengage said parts after each printing movement and normally maintain them disengaged, and a device for effecting said selective movement of the printing couple provided with means for tripping said trip device after selection of a type form to print the latter on the work. 130
8. The combination with a printing couple comprising a plurality of type forms and a platen having a relative selective movement to bring the type forms individually to position for co-operation with the platen and having also a relative printing

- movement, of continuously rotated power operated means, mechanism for connecting said rotated means with the printing couple to effect the printing movement thereof comprising rotary clutch parts, means tending to engage said parts, a trip device actuated by the driven clutch part for disengaging said parts, and a device for effecting said selective movement of the printing couple connected with said trip device and having a movement to trip the latter for engagement of said parts by said means.
14. The combination with a type carrier and platen having a relative selective movement to bring a plurality of type forms on the carrier individually to position for co-operation with the platen, said carrier having a rotary movement to print the selected forms, of rotary power operated means including a clutch part, a second clutch part on the carrier for engagement with said first part, a device comprising means for normally holding said clutch parts disengaged and for holding the carrier against rotation, and selective means movable to effect said selective movement of the carrier and platen having a connection with said device for actuating the same to release the carrier and to release said clutch parts for engagement with each other to rotate the carrier.
15. The combination with a type carrier and platen having a relative selective movement to bring a plurality of type forms on the carrier individually to position for co-operation with the platen, said carrier having a rotary movement to print the selected forms, of rotary power operated means including a clutch part, a second clutch part connected with the carrier and movable to and from engagement with said first part for intermittently rotating the carrier, means tending to engage said clutch parts, a stop device normally lying in the path of rotation of said second clutch part for disengaging said parts and stopping the rotation of said second part and carrier, selective means for effecting said selective movement of the carrier and platen, and mechanism actuated by said selective means for disengaging said device and second clutch part to effect rotation of the carrier.
16. The combination with a type carrier and platen having a relative selective movement to bring a plurality of type forms on the carrier individually to position for co-operation with the platen, said carrier having a rotary movement to print the selected forms, of rotary power operated means including a clutch part, a second clutch part co-operating with the first and connected with the carrier to rotate the latter, a stop device arranged to automatically disengage said clutch parts during rotation thereof, a trip device for rendering said stop device inactive, release means actuated by said ro-
- tary means for moving said trip device to inactive position, and selective means for effecting said selective movement of the carrier and platen having a connection with said trip device for actuating the latter to effect rotation of the carrier.
17. The combination with a printing apparatus having an intermittent printing movement, of continuously driven power operated means, a releasable positive connection between said power means and printing apparatus for effecting said intermittent printing movement, and a yielding braking connection between said printing apparatus and power means for maintaining a regulating load on the latter between printing movements of said apparatus.
18. The combination with a printing apparatus having an intermittent printing movement, of continuously driven power operated means, a positive clutch connecting said power means and printing apparatus and means for actuating the same to effect said intermittent printing movement, and a frictional braking connection between said printing apparatus and power means for automatically imposing a regulating load on the latter exclusively between printing movements of said apparatus.
19. The combination with printing means comprising a plurality of type forms and a platen having relative selective movement to bring said forms individually and the platen to printing position and having also a relative printing movement, of continuously driven power operated means having a releasable positive connection with the printing means for effecting said printing movement thereof and also a yielding connection therewith for maintaining a load on the power means between printing movements of said printing means, a device operating normally to automatically release said positive connection after said printing movement, and control means for effecting said selective movement of the printing means having also a connection with said device for disposing the same in inactive position.
20. The combination with a type carrier and platen having a relative selective movement to bring a plurality of type forms on the carrier individually to position for co-operation with the platen, said carrier having a rotary movement to print the selected forms, of continuously rotated power operated means having a positive clutch connection with the carrier for rotating the same and also a yielding clutch connection therewith for maintaining a load on the power means when the carrier is stationary, a stop device arranged normally to automatically disengage said positive connection and maintain the carrier stationary, and selective means for effecting said selective

movement of the carrier and platen having a connection with said stop device for moving the same to inactive position.

21. The combination with a type carrier and platen having a relative selective movement to bring a plurality of type forms on the carrier individually to position for co-operation with the platen, said carrier having a rotary movement to print the selected forms, of continuously rotated power operated means having a positive clutch connection with the carrier for rotating the same and also a yielding clutch connection therewith for maintaining a load on the

power means when the carrier is stationary, 15 a stop device arranged normally to automatically disengage said positive connection during rotation and to hold the carrier stationary, selective means for effecting said selective movement of the carrier and platen, 20 and mechanism actuated by said selective means in one position thereof for tripping said stop device to effect a single rotation of the carrier and in another position thereof for holding said stop device inactive to effect 25 continuous rotation of the carrier.

In testimony whereof I affix my signature.
WALTER B. PAYNE.
